(57) **CLAIM**

The ornamental design for a packaging bag for a fascia gun, as shown and described.

DESCRIPTION

The patent or application file contains drawings executed in color. Copies of this patent or patent application with color drawings will be provided by the Office upon request and payment of the necessary fee.

1.1 is a front view of a packaging bag for a fascia gun, showing my new design;

1.2 is a back view thereof;

1.3 is a left view thereof;

1.4 is a right view thereof;

1.5 is a top view thereof;

1.6 is a bottom view thereof; and

1.7 is a perspective view thereof.
